(57) **CLAIM**

The ornamental design of a operating handle for a closure element, as shown and described.

DESCRIPTION

FIG. 1 is a front, top, and side perspective view of my operating handle for a closure element design;

FIG. 2 is an elevation view of my operating handle for a closure element design from the side opposite that in FIG. 1; FIG. 3 is plan view of my operating handle for a closure element design;

FIG. 4 is an elevation view of my operating handle for a closure element design from the same side as in FIG. 1; FIG. 5 is a bottom view of my operating handle for a closure element design;

FIG. 6 is a front elevation view of my operating handle for a closure element design; and,

FIG. 7 is a rear elevation view of my operating handle for a closure element design.

The broken lines are for illustrative purposes only and forms no part of the claimed design.
